Company, East Pittsburgh, Pa., a corporation
of Pennsylvania

Application August 25, 1933, Serial No. 686,764

30 Claims. (Cl. 200—144)

My invention relates, generally, to electrical circuit breakers and it has particular relation to arc extinguishing apparatus therefor. My application Serial No. 83,260, filed June 3, 1936, is a continuation-in-part of this application.

In the past, it has been customary to provide an individual circuit breaker and mechanism for connecting a load device, such as a transformer, to a high-voltage system. This has necessitated the use of two individual sets of apparatus comprising the circuit breaker and the transformer which have required a considerable space for their occupancy. When a sub-station is located in the densely populated district where space is at a premium, such an arrangement causes the expense of the installation to be increased merely for the purpose of providing sufficient room to mount the necessary electrical apparatus.

In addition, when separate devices are provided, it has been necessary to provide for their separate insulation which is also an important factor in the economics of operation of a power distribution system.

It has been proposed to combine these two types of apparatus into a single unitary structure in order to reduce the required space therefor, and also to utilize the insulation of the load device for the circuit breaker device. However, this has led to considerable difficulty and it has heretofore been impractical until the provision of this invention for extinguishing the arcs formed on opening of the circuit breaker which will be set forth in detail hereinafter.

In general, I propose to mount the circuit breaker within the customary insulator bushings which are provided with a transformer for insulating the power conductors from the case or tank. This form of mounting inherently provides a relatively great degree of insulation, since it is particularly designed to withstand the voltages which are to be applied to the transformer windings. It is, therefore, unnecessary to provide additional insulation for the circuit breaker mechanism with the result that the cost of the combined unit of circuit breaker apparatus and load device is materially reduced. It will, of course, be apparent that the space requirements for a combination constructed in accordance with my invention will also be materially reduced.

The object of my invention, generally stated, is to provide circuit breaker equipment for a load device which shall be simple and efficient in operation and which may be readily and economically constructed and installed.

The principal object of my invention is to pro-

vide for incorporating a circuit breaker structure in the lead-in bushing of a load device, such for example, as a transformer.

Another object of my invention is to provide for opening the circuit to a load device in several series sections.

Still another object of my invention is to provide for rapidly extinguishing arcs formed between several series connected contact members by rotating the arcs through the agency of a radial magnetic field.

A further object of my invention is to provide for simultaneously opening several series connected contact members and extinguishing the arcs drawn therebetween by rotating them between grid plates by means of a radial magnetic field.

A still further object of my invention is to provide for uniformly distributing the potential among the arc extinguishing devices surrounding a plurality of series connected contact members when the arcs are extinct.

Other objects of my invention will in part be obvious and in part appear hereinafter.

My invention accordingly is disclosed in the embodiment hereof shown in the accompanying drawings and comprises the features of construction, combination of elements and arrangement of parts which will be exemplified in the construction hereinafter set forth and the scope of the application of which will be indicated in the appended claims.

For a more complete understanding of the nature and scope of my invention, reference may be had to the following detailed description taken in connection with the accompanying drawings, in which—

Figure 1 is a view, partly in side elevation and partly in section, illustrating the application of my invention to a transformer;

Fig. 2 is an enlarged sectional view showing, in part, the details of construction of my novel circuit breaker, certain duplicate elements being omitted for the sake of clearness;

Fig. 3 is a sectional view taken along the line III—III of Fig. 2; and

Figs. 4 through 8 illustrate certain constructional details used in the assembly of the arc extinguishing device illustrated in Fig. 2.

For the purpose of illustration, my invention has been shown in Fig. 1 as applied to a transformer for a load device. However, it will be readily understood that the application of my invention is not limited to use with a transformer and that it may be used with any other suitable

type of load device. It will also be understood that my invention may be utilized in the form of a suspension insulator mounted on a transmission line tower or the like, if it is so desired.

5 As illustrated, in Fig. 1 of the drawings, a transformer, shown generally at 10, is provided, having a core 11 and a winding 12 immersed in insulating oil 13 in the customary and well known manner. A tank 14 is provided for the 10 transformer 10 having a cover 15 on which lead-in bushings 16 may be mounted. The lead-in bushings 16 are mounted on the cover 15 and extend into the tank 14 as shown. The winding 12 is connected by means of conductors 17 to 15 the insulating bushings 16 in the usual manner. Connection with power lines 18 is had by means of terminals 19 mounted on the upper ends of the insulator bushings 16.

As will be more fully set forth hereinafter, 20 a circuit breaker is mounted within the insulator bushing 16 and an operating mechanism comprising an armature 20 and a winding 21 are provided, individual to each circuit breaker, for effecting its operation to either the open or the 25 closed position. The movement of the armatures 20 is communicated to the circuit breakers by means of lift rods 22. It will be understood that the control of the energization of the winding 21 may be effected by any well known control 30 means and, therefore, a detailed description of it will not be given in this specification.

Referring now particularly to Fig. 2 of the drawings, it will be observed that the circuit breaker structure, which may be mounted within 35 the insulator bushing 16, is shown. In order to more clearly illustrate the important details of my invention, the insulator bushing 16 is entirely omitted from this figure of the drawings and the supporting framework is shown in section. The entire mechanism illustrated in Fig. 2 40 may be mounted within the insulator bushing 16, as will be readily understood, thereby taking advantage of its insulating properties without necessitating the provision of additional insulating bushings for the circuit breaker structure 45 itself.

As illustrated, the frame, shown generally at 28, comprises upper and lower end plates 29 and 30, respectively, between which suitable holding 50 members for the circuit interrupter structure are provided. These holding members comprise the insulating rods 51 which engage the notches in the edges of the plates shown in Figs. 3 to 6, inclusive, and the insulating tube 31 having a ring 61 at each end, to lugs on which the end plates 29 and 30 are bolted. The terminal 19 is connected to an upper end cup 32 while the conductor 17 may be connected to a suitable lower end cup 33, the connections to which are not 55 shown in detail.

Between the upper and lower end cups 32 and 33, a plurality of fixed and movable contact members 34 and 35 are provided which are arranged to be connected in series circuit relation 60 by means of flexible shunts 36. It will be readily understood that the number of sets of contact members 34 and 35 will depend upon the voltage which is to be applied to the load device. Thus, if a relatively high voltage is to be applied it is 65 desirable to provide a relatively large number of contact members 34 and 35 in order to provide for more readily opening the circuit with a minimum of disturbance.

The fixed contact members 34 are secured to disks 37 around which windings 38 are disposed,

the purpose for which will be set forth in detail hereinafter.

As illustrated, the movable contact members 35 are mounted transversely of the lift rod 22 in suitable slotted openings 40 and are biased upwardly by means of springs 41 which are disposed between the underside of the movable contact members 35 and plugs 42 which are secured to the lift rod 22 by means of rivets 43. It will be observed that, as the lift rod 22 is moved downwardly, the movable contact members 35 will be moved downwardly when the ends of the slots 40 are encountered. However, until this engagement takes place, the contact members 34 and 35 will be maintained in engagement by means of 15 the springs 41.

The flexible shunts 36 are connected to coil plates 45 which are disposed above the windings 38 and which are more clearly illustrated in Figs. 6 and 8 of the drawings. It will then be observed 20 that the terminal 19 is connected to the conductor 17 through a plurality of series-connected separable contact members 34 and 35. Thus, when these contact members are moved to the open positions several air gaps are provided in 25 the circuit thereby splitting up the single arc, which would normally be formed, into several arcs provided that all of the contact members are opened simultaneously. The voltage stress which is applied to any particular set of contact 30 members is considerably reduced from that which would be applied if only a single set of contact members were used. Because of this arrangement, it is not necessary to separate the contact members 34 and 35 to the extent that 35 would be necessary if a single equivalent set of contact members were used.

When the lift rod 22 is moved downwardly, so that arcs individual to each of the sets of contact members 34 and 35 will be drawn, it is essential 40 that these arcs be extinguished as rapidly as possible in order to avoid damage to the circuit breaker. For this purpose, deionizing devices, shown generally at 47, are provided comprising a plurality of metal grid plates 48 preferably of 45 copper and more clearly illustrated in Fig. 5 of the drawings. The metal plates 48 are provided with openings 48a having tapered portions 48b for the purpose of providing a path for the arc which is formed between the contact members 50 34 and 35. As shown in Fig. 3 of the drawings, the movable contact members 35 are disposed within the openings 48a.

Only two of the deionizing devices 47 are illustrated in the drawings but it will be understood 55 that each set of contact members 34 and 35 is provided with one of them to provide for rapidly extinguishing the arcs drawn therebetween.

In order to provide for insulating the plates 48 from each other, an outer insulating ring 49 is 60 provided at the outer edge thereof while inner insulating segments 50 are provided around the openings 48a. These insulation pieces 49 and 50 are shown more clearly in Figs. 4 and 7 respectively of the drawings and their assembly with 65 the grid plate 48 is shown in Fig. 3. Insulating rods 51 are provided for lining up the elements of the deionizing devices 47 and securing them in position.

With a view to providing for rotating the arcs 70 formed between contact members 34 and 35, until they are extinguished, the windings 38 are provided as hereinbefore set forth, which are arranged to generate a radial field between the grid plates 48 on flow of current therethrough. 75

The radial field generated by the windings 38 causes the several arcs to traverse paths which may be indicated by the dotted lines 52 or 53 and 54 in Fig. 3. It will be readily understood that the arcs may be formed at either end of the movable contact members 35 and that they may follow either of the paths indicated by the dotted lines 52 and 53 to intersect the paths indicated by the dotted line 54. It will be understood that the inner terminals of the windings 38 may be connected to the disks 37 which are connected in turn to the fixed contact members 34 while the outer terminals thereof may be connected to the coil plates 45 beneath the windings 38 or vice versa, as the case may be.

In order to insure that the arcs formed between the contact members 34 and 35 are transferred to the plates 48, the coil plates 45 above the coils are provided with upstanding leaf portions or tabs 56 which are disposed along the paths of the arcs between these contact members and to which the arcs tend to transfer as the contact members 35 are moved to the open positions. The other end of the arc transfers from the fixed contact 34 to the coil plates 45' below the coils. The arc current is thus caused to quickly flow through the windings 38 thereby instantaneously establishing the desired radial field for rotating the several arcs between the grid plates 48. It will be understood that the windings 38 are normally de-energized and that load current does not flow through them except when arcs have formed between the contact members 34 and 35 and transferred to the coil plates 45 and 45' which form arc terminal members extending from the annular path to points closely adjacent the contacts 34 and 35 in order that the arc may quickly transfer from the contacts 34 and 35 to the coil plates 45 and 45'.

Since the direction of the radial field on the lower sides of the windings 38 is opposite to its direction on the upper sides, alternate deionizing devices are provided with the grid plates 48 in reversed position. Thus, on one side of the windings 38, the arcs will be rotated in one direction while on the other side they will be rotated in the opposite direction. The terminals of the windings 38 are properly connected so that the direction of fields generated thereby between them will be the same.

Assuming that operating potential is applied to the power conductors 18 and load current is being supplied to the transformer 10, the circuit breaker may be operated to the open position by permitting the lift rod 22 to move downwardly when the winding 21 is de-energized. As soon as the lift rod 22 is moved downwardly, arcs will be formed between the several contact members 34 and 35 and the ends of the arc will be transferred from the contact members 34 and 35 to the coil plates 45, and to the arcing leaves 56 of the coil plates 45 as they are passed by the movable contact members 35. Current will then be caused to flow through the windings 38, thereby setting up a radial field between the grid plates 48 and causing the arcs to be split up into several series of short arcs between these plates and to travel along the paths indicated by the dotted lines 52 or 53 and 54. The rotation of these short arcs will be continued by the respective radial fields generated by the windings 38 until they are extinguished.

When the arcs are extinguished, it will be apparent that the potential distribution between the series connected contact members and along

the plates 48 will be non-uniform due to their capacity effect. In order to prevent this non-uniform distribution of potential, static shield layers 59 and 60 of conducting material are provided along the plates 48 but insulated therefrom by being embedded in the tube 31, thereby serving to more uniformly distribute the potential along the structure.

Since certain further changes may be made in the above construction and different embodiments of the invention may be made without departing from the scope thereof, it is intended that all matter contained in the above description or shown in the accompanying drawings shall be interpreted as illustrative and not in a limiting sense.

I claim as my invention:

1. A circuit breaker comprising, in combination, a plurality of sets of fixed and movable contact members between which a plurality of arcs may be drawn, said sets of contact members being connected in series circuit relation, and arc extinguishing means individual to each set of contact members and disposed adjacent to the arc paths therebetween, said arc extinguishing means comprising a plurality of metal plates adapted to subdivide the arcs into a series of short arcs, said metal plates providing recurrent paths for the short arcs and said metal plates having openings therethrough, and operating means movable in said openings for actuating the movable contact members to the open position.

2. A circuit breaker comprising, in combination, a plurality of sets of fixed and movable contact members between which a plurality of arcs may be drawn, said sets of contact members being connected in series circuit relation, operating means for actuating said contact members to either the open or the closed position, and arc extinguishing means individual to each of a plurality of said sets of contact members comprising a plurality of metal plates each having an annular portion extending around said contact members and disposed to subdivide the arcs into a plurality of series of short arcs, and means for causing said short arcs to move about recurrent paths on said annular portions of the plates for extinguishing the short arcs.

3. A circuit breaker comprising, in combination, a plurality of sets of fixed and movable contact members between which a plurality of arcs may be drawn, said sets of contact members being connected in series circuit relation, operating means for actuating said contact members to either the open or the closed position, a plurality of sets of metal plates, each set being individual to one of said plurality of sets of contact members and adapted to subdivide the arcs into a series of short arcs, said plates being so formed as to provide recurrent paths surrounding said contact members for said short arcs, and means for creating a radial magnetic field between said plates for causing said short arcs to rotate along said recurrent paths.

4. A circuit breaker comprising, in combination, a plurality of sets of fixed and movable contact members between which a plurality of arcs may be drawn, said sets of contact members being connected in series circuit relation, operating means for actuating said contact members to either the open or the closed position, a plurality of sets of metal plates each set being individual to and surrounding one set of contact members and disposed to subdivide the arcs into a plurality of series of short arcs, the configura-

tion of said plates being such as to provide recurrent paths around said contact members for said short arcs, and generating means disposed substantially concentrically with the axis of movement of said movable contact members for creating a radial magnetic field between said plates for causing said short arcs to rotate along said recurrent paths.

5. A circuit breaker comprising, in combination, a plurality of sets of fixed and movable contact members between which a plurality of arcs may be drawn, said sets of contact members being connected in series circuit relation, operating means for actuating said contact members to either the open or the closed position, and a plurality of arc extinguishing devices, each being individual to one set of contact members and each comprising a plurality of metal plates surrounding the contact members and operating means and disposed to subdivide the arc drawn therebetween into a series of short arcs, the shape of said metal plates being such as to provide recurrent paths around said contact members for said short arcs, and a winding connected in series circuit relation with said plates and adapted on flow of current therethrough to generate a radial field between said plates for causing said short arcs to rotate along said recurrent paths.

6. A circuit breaker comprising, in combination, a plurality of sets of fixed and movable contact members between which a plurality of arcs may be drawn, said sets of contact members being connected in series circuit relation, operating means for actuating said contact members to either the open or the closed position, and a plurality of arc extinguishing devices, each being individual to one set of contact members and each comprising a plurality of metal plates surrounding the contact members and disposed to subdivide the arc drawn therebetween into a series of short arcs, the shape of said metal plates being such as to provide recurrent paths for said short arcs, a winding connected in series circuit relation with said plates and adapted on flow of current therethrough to generate a radial field between said plates for causing said short arcs to rotate along said recurrent paths, and an arc horn positioned inside of the recurrent paths provided by said plates for facilitating the transfer of the arc from the movable contact member to the metal plates surrounding it.

7. A circuit breaker comprising, in combination, a plurality of sets of fixed and movable contact members between which a plurality of arcs may be drawn, said sets of contact members being connected in series circuit relation, operating means for actuating said contact members to either the open or the closed position, and a plurality of arc extinguishing devices, each being individual to one set of contact members and each comprising a stack of metal plates surrounding the contact members and disposed to subdivide the arc drawn therebetween into a series of short arcs, the shape of said metal plates being such as to provide recurrent paths for said short arcs, a winding connected in series circuit relation with said plates and adapted on flow of current therethrough to generate a radial field between said plates for causing said short arcs to rotate along said recurrent paths, and a plurality of arcing plates disposed at intervals in said stack and each being provided with an upstanding portion disposed adjacent the path of one of the movable contact members for effecting the

transfer of the arc to the upstanding portions to facilitate its transfer to the metal plates.

8. In a circuit breaker, in combination, a fixed and a movable contact member between which an arc may be drawn, a plurality of metal plates surrounding the contact members for subdividing the arc drawn therebetween into a series of short arcs, and an arcing plate provided with an upstanding portion disposed adjacent the path of the movable contact member for effecting the transfer of the arc thereto for facilitating its transfer to the metal plates.

9. In a circuit breaker, in combination, a fixed and a movable contact member between which an arc may be drawn, a plurality of metal plates completely surrounding the contact members for subdividing the arc drawn therebetween into a series of short arcs, the shape of said metal plates being such as to provide recurrent paths for said short arcs, a winding connected in series circuit relation with said plates and adapted on flow of current therethrough to generate a radial field between said plates for causing said short arcs to rotate along said recurrent paths, and an arcing member provided with a portion extending from said recurrent path into the inside thereof adjacent to the path of the movable contact member for effecting the transfer of the arc thereto for facilitating its transfer to the metal plates.

10. Electrical apparatus comprising, in combination, a load device, a plurality of conductors for connecting the load device to a current source, an insulator bushing surrounding at least one of said conductors and incorporated as a part of the load device, circuit breaker means mounted within said insulator bushing comprising a plurality of fixed and movable contact members connected in series circuit relation, and operating means including a rod movable longitudinally in said insulator bushing and operatively connected to each of a plurality of said movable contact members for actuating them simultaneously to either the open or the closed position, said operating means having its moving parts enclosed within said electrical apparatus.

11. Electrical apparatus comprising, in combination, a load device, a plurality of conductors for connecting the load device to a current source, an insulator bushing surrounding at least one of said conductors and incorporated as a part of the load device, circuit breaker means mounted within said insulator bushing comprising a plurality of sets of series-connected fixed and movable contact members between which a plurality of arcs may be drawn, and arc extinguishing means for each of a plurality of said sets of contact members and disposed adjacent to the arc paths therebetween for extinguishing said arcs, and an operating rod movable in said insulator bushing and connected to each of said movable contacts for simultaneously actuating said contact members to either the open or the closed position.

12. Electrical apparatus comprising, in combination, a load device, a plurality of conductors for connecting the load device to a current source, an insulator bushing surrounding at least one of said conductors and incorporated as a part of the load device, circuit breaker means mounted within said insulator bushing comprising a plurality of sets of series-connected fixed and movable contact members between which a plurality of arcs may be drawn, a plurality of sets of metal plates, each set being individual to one set of

contact members for subdividing said arcs into a series of short arcs, said plates being so formed as to provide recurrent paths for said short arcs, and means for creating a radial magnetic field 5 between said plates for causing said short arcs to rotate along said recurrent paths, and operating means connected to each of said movable contact members for actuating said movable contact members to either the open or the closed 10 position.

13. Electrical apparatus comprising, in combination, a load device, a plurality of conductors for connecting the load device to a current source, an insulator bushing surrounding at least 15 one of said conductors and incorporated as a part of the load device, circuit breaker means mounted within said insulator bushing comprising a plurality of sets of series connected fixed and movable contact members between which a 20 plurality of arcs may be drawn, a plurality of sets of metal plates, each set being individual to and surrounding one set of contact members for subdividing the arcs into a plurality of series of short arcs, the configuration of said plates 25 being such as to provide recurrent paths for said short arcs, and a winding connected in series circuit relation with said plates and disposed on flow of current therethrough to generate a radial field between said plates for causing said short 30 arcs to rotate along said recurrent paths, said plates having openings therethrough within the outer periphery of said recurrent paths, and operating means movable through said openings for actuating said contact members to either the 35 open or the closed position.

14. In a circuit breaker, in combination, fixed and movable contact members between which an arc may be drawn, a plurality of spaced apart metal plates adjacent the contact members for subdividing the arc drawn therebetween into a series of short arcs, a normally deenergized winding adapted to be connected in series circuit relation with said plates for generating a radial field therebetween, a pair of arc terminal members 40 one of which extends to a point closely adjacent to said fixed contact and the other of which comprises an arcing horn extending to a point closely adjacent the path of the movable contact member for effecting the transfer of the 45 arc to the arc horn, and said winding for generating a radial field being energized upon the transfer of the arc to said arc terminal members.

15. In a circuit interrupter, means for establishing an arc, means for extinguishing said arc 55 including a plurality of spaced plates of conducting material for splitting up the arc into short arcs, conducting means which when energized causes said short arcs to rotate on said plates, an arc terminal member having a portion extending 60 to a point closely adjacent the path where said arc is initially established to permit the arc to immediately transfer to the arc terminal member, and said conducting means which causes said arcs to rotate being normally deenergized and being energized upon the transfer of one end of the 65 arc from the means for establishing the arc to said arc terminal member.

16. In a circuit interrupter, means for establishing an arc, means for extinguishing said arc, 70 including conducting members providing an annular path about which the arc may be rotated, conducting means which when energized sets up a radial magnetic field for rotating the arc about said annular path, arc terminal means extending 75 from said annular path to a point closely ad-

jacent the path where said arc is initially established to permit the arc to immediately transfer to the arc terminal member, said arc terminal means being connected to said conducting means and causing energization thereof upon the transfer of one end of the arc to said arc terminal means, and said arc terminal means being positioned within the radial magnetic field set up by said conducting means whereby the arc is moved thereon by the radial magnetic field. 10

17. In a circuit interrupter, means for establishing an arc, means for extinguishing said arc including conducting members providing an annular path about which the arc may be rotated, said means for establishing the arc being positioned within said annular path, conducting means which when energized sets up a radial magnetic field for rotating the arc about said annular path, arc terminal means extending from said annular path toward the center thereof to a point 20 closely adjacent the path where said arc is initially established, said arc terminal means being connected to said conducting means and causing energization thereof upon the transfer of one end of the arc to said arc terminal means, and said arc 25 terminal means being positioned within the radial magnetic field set up by said conducting means whereby the arc is moved thereon by the radial magnetic field.

18. In a circuit interrupter, a plurality of members of conducting material, each of said members of conducting material providing a recurrent path for an arc, and having an opening therethrough at one side of said recurrent path, means for setting up a radial magnetic field across said recurrent path and across said openings, means for initially establishing an arc in said opening, and said means for setting up the radial magnetic field causing it to be set up at least while said arc is still in said opening whereby said radial magnetic field moves the arc from said opening into 30 said recurrent path and rotates it thereabout. 35

19. In a circuit interrupter, a plurality of plates of conducting material, each of said plates providing an annular path for an arc and having an 40 opening therethrough at one side of said annular path, a plurality of said openings each having a generally V-shaped portion with the apex of the V pointing toward the annular path for the arc, means for initially causing an arc in said opening, and means for setting up a radial magnetic field across said opening and across said annular path while the arc plays in the opening for moving the arc in the opening toward the apex of the V-shaped portion and in said annular path. 45

20. In a circuit interrupter, a plurality of members of conducting material each providing an annular arc path, a plurality of said members each having an opening therethrough inside of said annular path, means for causing an arc in 50 said opening inside of said annular path, and means for moving said arc outwardly from said opening into said annular path and moving it thereabout. 60

21. In a circuit interrupter, a plurality of plates of conducting material each providing an annular path for the arc, a plurality of said plates each having an opening therethrough inside of said annular path, means for causing an arc through 65 said openings inside of said annular path, means energized at least shortly after said arc is drawn and while it plays through said openings for setting up a radial magnetic field across said openings and across said annular path, said radial magnetic field moving said arc from said opening 70 75

into said annular path and splitting it up into short arcs, and causing rotation of said short arcs about said annular path.

22. In a circuit interrupter, a pair of separable contacts for drawing an arc, means for extinguishing the arc including a coil for causing a radial magnetic field across the arc path, said coil having an opening through the central portion thereof, and an operating rod movable in said opening through the coil for actuating said separable contacts.

23. In a circuit interrupter, a plurality of arc extinguishing structures, a plurality of pairs of separable contact members for establishing an arc in each of said structures, a plurality of coils for moving the arcs in an arcuate path in said arc extinguishing structures, and an operating rod movable through the central portion of said arc extinguishing structures and through said coils

20 for actuating said separable contact members.

24. In a circuit interrupter, a stack of axially aligned arc extinguishing structures each including a pair of arcuate arc terminal members, a movable arc drawing member for establishing an arc between each pair of arcuate arc terminal members and a coil for moving the arcs around said arcuate arc terminal members, an opening extending through said stack of arc extinguishing structures within said arcuate arc terminal members and within said coils, and an operating rod movable through said opening for actuating said movable arc drawing members.

25. In a circuit interrupter, a plurality of groups of plate members, each group having a pair of arcuate arc terminal members and a movable arc drawing member for establishing an arc thereacross, an opening extending longitudinally through said plurality of groups of plate members adjacent to the center of said arcuate arc terminal members, and an operating member movable through said opening to actuate said movable arc drawing members.

26. In a circuit interrupter, a stack of plate members, a plurality of arc drawing members for establishing a plurality of arcs among said plate members, an opening through said plate members adjacent the center thereof, an operating rod extending through said opening for actuating said plurality of arc drawing members, and means for causing said arcs to move in an arcuate path around said operating rod.

27. In a circuit interrupter, a tubular member of insulating material, a plurality of arc extinguishing means stacked in said tubular member of insulating material, means for establishing one or more arcs extending longitudinally of said tubular member of insulating material, an operat-

ing rod movable longitudinally in said tubular member of insulating material for actuating said arc establishing means, and means for causing movement of the arc in an arcuate path about an axis extending longitudinally through the 5 tubular member of insulating material.

28. In a circuit interrupter, a tubular member of insulating material, a plurality of arc extinguishing means stacked in said tubular member of insulating material, a plurality of arc drawing members movable to establish a plurality of series-related arcs extending longitudinally of the tubular member of insulating material, an operating rod movable longitudinally in said tubular member of insulating material for actuating said plurality of arc drawing members, and means for causing movement of said arcs in an arcuate path about said operating rod.

29. Electrical apparatus comprising, in combination, a load device having a metal housing, a plurality of conductors for connecting the load device to a current source, an insulator bushing surrounding at least one of said conductors and extending through said metal housing and thereby incorporated as a part of the load device, circuit breaker means mounted within said insulator bushing comprising a plurality of fixed and movable contact members connected in series circuit relation, and operating means including a rod movable longitudinally in said insulator bushing and operatively connected to each of a plurality of said movable contact members for actuating them simultaneously to either the open or the closed position, said operating means having its moving parts enclosed within said electrical apparatus.

30. Electrical apparatus comprising, in combination, a load device having a metal housing, a plurality of conductors for connecting the load device to a current source, an insulator bushing surrounding at least one of said conductors and extending through the metal housing and incorporated as a part of the load device, circuit breaker means mounted within said insulator bushing comprising a plurality of sets of series-connected fixed and movable contact members between which a plurality of arcs may be drawn, and arc-extinguishing means for each of a plurality of said sets of contact members and disposed adjacent to the arc paths therebetween for extinguishing said arcs, and an operating rod movable in said insulator bushing and connected to each of said movable contacts for simultaneously actuating said contact members to either the open or the closed position.

BENJAMIN P. BAKER.
